SCARF SQUARE AND TRIANGLE

Sophia Swartz, New York, N. Y.

Application May 26, 1954, Serial No. 432,515

6 Claims. (Cl. 2—48)

This invention relates to a garment of very simple construction that can be produced very quickly, inexpensively and adapted to be put to numerous useful as well as decorative purposes.

The simplicity of construction of this novel garment makes it very useful and is very easy and economical to manufacture and therefore can serve the masses because it can be acquired reasonably and yet worn in many different ways, on various parts of the body, while engaging in different tasks, on different occasions.

Teen-agers and children will find my garment indispensable, particularly at camping to wear as a sun suit or as a babushka or neck scarf etc. Adults will find it useful in traveling when a "quick change" is needed and especially for those "air-minded travelers" who must curtail luggage.

It will therefore be observed that my garment is so constructed to make it useful and in appearance, render it attractive exposing back, shoulders and arms in brassiere-like fashion, to sunlight and air, with geometric symmetry and which is gentle to the natural undulations of the figure, even when worn over a blouse or dress for warmth or decoration.

Fig. 1 is a plan view of the garment.

Fig. 2 shows triangle halter.

Fig. 3 shows garment with apron effect.

Fig. 4 is rear view of the garment.

1 shows outer line.

2 shows point where to cut.

3 opposite end of cut.

4 shows line which may or may not be detached.

5 indicates line for severing to make triangle, leaving opposite side plain on which the process may be repeated to make another garment by repeating the cutting of the neckline.

The collar encircling the neck being of a strap effect, squarish or roundish lies flat and hugs the neck and exposes the back and shoulders and chest and is therefore useful as a sun suit and when worn under a sweater or jacket in place of a blouse is not bulky and gives wearer a comfortable feeling and attractive slim look, important to a woman's appearance.

It will be observed that my garment is so constructed as to render it useful in many ways and in appearance give a figure a slim and attractive appearance, rendering it appropriate for beach wear, for a swim, or to lounge around when one wishes to expose the skin to the sun and air for health or to acquire a tanned skin.

In the winter it may be worn over a dress as a sort of chest protector adding warmth to the body especially when made of wool tricot or other warm materials. It can also be worn over a blouse or dress for decorative effect when garment is made of some glamorous material.

The garment may also be worn to give an apron effect over a dress when one engages in household tasks and it does not obstruct an attractive blouse or dress one may be wearing, but merely covers the parts that may get soiled while engaging in such tasks. The simple con-

2

struction of the apron-like effect on the figure, gives wearer an attractive slim look which women desire. An old dress of simple construction may be glamorized and enhanced when materials used in making my garment are decorative fabrics.

In its simplest form my garment may be worn as a babushka over the head as a sash about the waist, as an ascot about the neck etc. The triangle form allows air to get to the hair through the slits of the apex of one of the corners, and the pony tail may be put through the opening, when worn by children and teen-agers.

The garment will serve children's needs as well as teen-agers and adults made according to their dimensions, but no exact size is necessary.

The finishing of the garment about the edges and slits may be done in a number of ways, hand rolled, banded, hemstitched, fringed, etc.

The slits around the edge of one of the apexes to form the neck band create a collar effect and yields a detachable piece which may be severed or left attached as one may desire.

The contour of the garment and neck line may be round or of a square effect.

When suitable plastic sheet, polyethylene, and other material involving no threads are used for the garment, the corners should be cut round instead of square at the chest and back of the neck and the foldable piece removed will then result in a rounded neck appearance instead of square and if left with a raw edge, which is non-raveling in such materials to avoid expense, it will be less likely to tear and wear satisfactorily.

The same cut may be applied to materials involving thread texture when desired to give the neckline a round look instead of a square look.

35 I claim:

1. A scarf body having a relatively narrow end portion and marginal side edge diverging outwardly from the said end portion, the said scarf body being provided with a pair of slits intersecting each other adjacent the said

40 end portion, the said slits being of substantially the same length, each of the slits being formed adjacent one of the marginal edge portions of the scarf to form a pair of strap members, the material between the said slits being foldable along a line joining the free ends of the slits to

45 form a neck opening, the material between the ends of the said side edge of the scarf body being of a length to form a body encircling member, the depth of the scarf between the lines joining the ends of the said slits and the ends of the side edges of the scarf body being of a dimension to provide a bust and midriff covering portion.

2. A scarf body of substantially rectangular shape, having substantially straight sides, the said scarf body adjacent the intersection of two of the sides being provided with a pair of slits intersecting each other adjacent the said corner, the said slits being of substantially the same length, each of the slits being formed adjacent one of the marginal edge portions of the scarf to form a connected pair of relatively narrow strap members, the material between the scarf slits being foldable along a line

50 joining the free ends of the slits to form a neck opening, the material between the ends of the said side edges of the scarf being of a length to form a waist encircling member, the depth of the scarf between the lines joining the ends of the said slits and the ends of the side edges of the scarf body being of a dimension to provide a bust midriff covering portion, said scarf body having a portion extending below the line joining the said ends of the side edges to form an apron.

55 3. The scarf body as set forth in claim 2 in which the slits are made continuous.

60 4. The scarf body as set forth in claim 2 in which the

65

foldable piece of the fabric at the neck resulting from the slits is removable.

5. The scarf body as set forth in claim 1 in which the slits are made continuous to give the neck line, front and back a round appearance and removing the foldable piece resulting from the cut of the neck. 5

6. The scarf body as set forth in claim 2 in which the slits are made continuous to give the neckline, front and back and shoulder a round appearance and removing the foldable piece resulting from the cut at the neck. 10
